UNITED STATES PATENT OFFICE.

ROBERT H. ENGLE, OF TRENTON, NEW JERSEY.

FURNACE FOR THE DISTILLATION OF METALS.

1,180,118.

Specification of Letters Patent. Patented Apr. 18, 1916.

Application filed November 26, 1915. Serial No. 63,458.

To all whom it may concern:

Be it known that I, ROBERT H. ENGLE, a citizen of the United States, residing in Trenton, New Jersey, have invented certain improvements in Furnaces for the Distillation of Metals, of which the following is a specification.

My invention relates to a furnace for the purification of metals by distillation, the objects of my invention being to insure the quick and effective heating of the retort or retorts containing the metal, to provide for the compact grouping of a series of such retorts, and to simplify and cheapen the construction of a furnace having such series of retorts. These objects I attain in the manner hereinafter set forth, reference being had to the accompanying drawings, in which—

Figure 1 is a transverse vertical section of a furnace constructed in accordance with my invention; Fig. 2 is a horizontal section of the same on the line *a—a*, Fig. 1, Fig. 3 is a vertical section of one of the retorts and of the fireplace associated therewith, said section being taken on the line *b—b*, Fig. 1, and Fig. 4 is a horizontal section similar to Fig. 2 but on a smaller scale and omitting the retorts, this view illustrating a modification of the invention.

The furnace has a central stack structure 1 containing a stack chamber 2 and providing a seat for the metal stack 3 when the same is used. Radiating from the central stack structure are a series of fireplaces (eight in the present instance) each of these fireplaces having a combustion chamber 4, a grate 5, and an ash pit 6, and crossing each combustion chamber from back to front is a retort 7 whose neck projects through the front wall of the combustion chamber for the attachment thereto of the usual condensing neck, such as shown by dotted lines in Fig. 1.

Each of the combustion chambers is connected to the chamber 2 by means of a flue system comprising a descending flue 8 which is in communication at the top with the combustion chamber 4 through a flue 9 and at the bottom with the stack chamber 2 through a flue 10, the inner end of the retort being exposed to the products of combustion descending the flue 8, as shown in Fig. 1. The front wall of the fireplace is inclined backwardly from bottom to top, so as to permit the desired projection of the neck of the re-

tort, and to deflect toward the flue 9 the products of combustion rising in the chamber 4.

The descending flue is deflected forwardly in line with the inner end of the retort by means of a projection 11 formed on the stack structure 1, as shown in Fig. 1, hence the products of combustion in each fireplace are caused to pass first around that portion of the retort contained in said combustion chamber and then to descend the flue 8, and in traversing said flue are deflected into contact with the inner end of the retort, thus insuring contact of the products of combustion with all portions of the retort not actually embedded in the supporting walls, the result being that the contents of the retort not only have their temperature quickly raised to the distillation point but such distillation process is quickly completed. The lower end of each descending flue 8 is also in communication, through a short flue 12, with the ash pit 6 of its corresponding fireplace, and said flue 12 contains a check draft damper 13 which may be opened when it is desired to check the draft through the flue 8 or closed when full draft through said flue 8 is required.

The stack chamber 2 extends below the flues 10 and the lower portion of said stack chamber communicates with a tunnel 14 through which access may be had to the interior of the stack chamber for cleaning the same, or for other purposes, the inner end of said tunnel being normally closed by a door 15.

While I have shown my invention as applied to a furnace having the fireplaces and retorts grouped around a central stack, and while I prefer this arrangement because it simplifies construction and reduces cost, the flue system which I have described can with like good results be employed in connection with a furnace having but a single fireplace.

In the construction of the furnace heretofore described and shown each retort is acted upon only by the products of combustion from its own fireplace but if it is desired to mingle the products of combustion from the different fireplaces and then distribute such mixed products of combustion to the various descending flues 8, this can readily be accomplished by providing, instead of the separate upper flues 9, an

annular flue 16 extending completely around the furnace and communicating with each of the flues 8 and 9, as shown in Fig. 4.

I claim;

- 5 1. A distillation furnace having a stack chamber, a fireplace at one side thereof, a back flue communicating at the top with the combustion chamber of said fireplace and at the bottom with the stack chamber, and a retort mounted in said fireplace so as to extend across the combustion chamber thereof, the inner end of said retort being exposed to the products of combustion descending the back flue.
- 10 15. 2. A distillation-furnace having a stack chamber, a fireplace at one side thereof, a back flue communicating at the top with the combustion chamber of said fireplace and at the bottom with the stack chamber, and a retort mounted in said fireplace so as to extend across the combustion chamber thereof, the inner end of said retort being exposed to the products of combustion descending said back flue, and the latter having therein a projection for deflecting said descending products of combustion forwardly against said inner end of the retort.
- 15 20. 3. A distillation furnace having a stack chamber, a fireplace at one side thereof, a back flue communicating at the top with the combustion chamber of said fireplace and at the bottom with the stack chamber and also with the ash pit of the fireplace, a check draft damper for opening or closing the latter communication, and a retort mounted in the fireplace so as to extend across the combustion chamber thereof, the

inner end of said retort being exposed to the products of combustion descending said back flue.

4. The combination, in a distillation furnace, of a stack chamber, a fireplace at one side thereof, said fireplace having a backwardly inclined front wall, a back flue communicating at the top with the combustion chamber of said fireplace, and at the bottom with said stack chamber, and a retort mounted in said fireplace so as to extend across the combustion chamber thereof, the inner end of said retort being exposed to the products of combustion descending said back flue and the neck of the retort projecting through the backwardly inclined front wall of the fireplace.

5. The combination, in a distillation furnace, of a central stack structure with chamber therein, a series of fireplaces grouped around said stack structure, a series of descending flues each communicating at the top with the combustion chamber of one of the fireplaces and at the bottom with the stack chamber, and retorts mounted in said fireplaces so as to extend across the combustion chambers thereof, each of said retorts being exposed at its inner end to its respective descending flue.

In testimony whereof, I have signed my name to this specification, in the presence of two subscribing witnesses.

ROBT. H. ENGLE.
